(57) **CLAIM**

The ornamental design for a scalloped cigarette packet, as shown.

DESCRIPTION

FIG. 1 is a perspective view of the scalloped cigarette packet showing our new design;

FIG. 2 is a top plan view thereof;

FIG. 3 is a rear view thereof;

FIG. 4 is a right side view thereof; and

FIG. 5 is a front view thereof;

FIG. 6 is a cross-sectional view along line 6—6 of FIG. 5; and,

FIG. 7 is a perspective view in an alternative configuration (with lid opened).

The bottom plan view corresponds to the top plan view, and the left side view is a mirror image of the right side view.
